(57) **CLAIM**

The ornamental design for a magnet accessory, as shown and described.

DESCRIPTION

FIG. 1 is a front perspective view of a magnet accessory illustrating a first embodiment of our new design;

FIG. 2 is a front view of the first embodiment of FIG. 1; FIG. 3 is a rear view of the first embodiment of FIG. 1; FIG. 4 is a left side view of the first embodiment of FIG. 1; FIG. 5 is a right side view of the first embodiment of FIG. 1;

FIG. 6 is a top view of the first embodiment of FIG. 1; FIG. 7 is a bottom view of the first embodiment of FIG. 1; FIG. 8 is a front perspective view of a magnet accessory illustrating a second embodiment of our new design;

FIG. 9 is a front view of the second embodiment of FIG. 8; FIG. 10 is a rear view of the second embodiment of FIG. 8; FIG. 11 is a left side view of the second embodiment of FIG. 8;

FIG. 12 is a right side view of the second embodiment of FIG. 8;

FIG. 13 is a top view of the second embodiment of FIG. 8; and,

FIG. 14 is a bottom view of the second embodiment of FIG. 8.

The broken lines show portions of the magnet accessory that form no part of the claimed design; the broken lines form no part of the claimed design.
